(57) **CLAIM**

The ornamental design for the speaker for automobile, as shown and described.

DESCRIPTION

FIG. 1 is a perspective view of a speaker for automobile showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a front view thereof with the grille attached for ease of illustration.

The broken lines adjacent the shaded areas in FIG. 1 and the broken lines adjacent the screen in FIG. 8 represent the bounds of the claimed design while all other broken lines are directed to environment and are for illustrative purposes only; the broken lines form no part of the claimed design.
